UNITED STATES PATENT OFFICE.

GEORGE A. MORRIS AND CHARLES SPENCER FALLOT, OF PORT HANEY, BRITISH COLUMBIA, CANADA.

RECORDING DEVICE FOR FARM USE.

Application filed August 23, 1926. Serial No. 130,978.

This invention relates to a recording device for the use of farmers and others who require to make systematic records of milk production, eggs, fruit or the like when the use of a book for such records would be unsuitable.

The object of the invention is to simplify the use of a form or schedule, so that these are always available for use in a handy form and are retained in a cleanly condition for future reference.

Further objects are that only the portion of the record actually in use is exposed and does not need to come in contact with the hands of the recorder; also that the permanent factors of the record are conveniently available for instant comparison; also the device is in a handy portable form for hanging upon the wall and can be instantly made dust-proof until the time of next requirement.

In carrying out our invention we adopt a plain, cylindrical member of such a diameter and length that the recording chart makes one convolution upon it.

The cylinder is secured to a light rod terminating in a milled head which forms a handle for slowly revolving the member which is mounted in a rectangular trough-like box, the upper portion of which is made hingeable for the convenient reception of the cylindrical member and at the same time provide a hand rest and a record stand for the use of the operator or recorder.

The cylinder is held in position and kept from revolving by a simple locking pin, which engages the notched periphery of the cylinder end flange whenever the weight of the wrist is applied to the hand rest when writing.

The invention is clearly shown by the accompanying drawings, which form part of this application and in which:

Fig. 1 is a front elevation of the device.

Fig. 2, an end elevation showing the top covers partly opened, and

Fig. 3, an end view of the device in the operating condition with a strip of the record chart exposed for writing upon.

Taking these in detail, the hollow revolvable cylinder (1) is mounted upon and secured to the central rod (2), this latter terminating in a milled handle (3). The cylinder revolves in the bearings at (4).

The rectangular box or trough is marked

(5). This is rounded at the front following the contour of the cylinder, the upper front quadrant of this portion being folded back to provide the wrist support (6).

The back of the receptacle (5) is continued to form a wall hanger having the slotted holes (7). The back portion of the top lid is set up to form the sloping stand (8) for the reception of a reference slip on the face (10), which is secured by the wire clips (11).

This slip would form the permanent headings for the record secured around the cylinder (1), so that each column of the latter at the writing position (9) is always adjacent to its correct designation.

The cylinder flange at one end is notched or serrated, as shown at (14), so that the projecting stud (13) may engage these recesses whenever the wrist is laid upon the slope (6) to make the record.

The surface of the record is the circular line (15) forming the periphery of the cylinder (1). The front top quadrant (16) is hinged at (17), the back portion of the lid being hinged at (18) and (19).

The operation of the device is in this wise, taking for instance the making of a milk record: Two lids are opened out, as shown in Fig. 2, and the cylinder (1) withdrawn, the record schedule is secured to the cylinder and carries a number of lines parallel to the axis of the cylinder and corresponding to the days of the month, the lines being intersected at right angles by lines which leave a space for each cow, the spaces being coincident with those of the flat horizontal strip (10) secured by the wire clips (11), each space being set apart for one particular cow and designated by number.

The cylinder is then replaced, the front quadrant (16) set back into position, also the top lid, both being as shown in Fig. 3. Records can then be made in the exposed space (9), the wrist resting upon the slope (6) and thereby securing the notched flange from movement. When the record is completed the lids are closed until the time of the next milking.

What we claim as our invention and desire to be protected in by Letters Patent, is:—

In a farmer's recording device consisting of a record carrying cylinder revolvable in a casing on which is fixed a partial and cor-

responding record the combination comprising, a semicircular front on the said casing, the said front being divided horizontally by a hinge on a horizontal plane passing through the axis of the same semicircle, the upper part of said front forming a movable quadrant, the said quadrant carrying a flat tangential member adapted to act as a wrist support, the rearward top of said casing being hinged to the casing along its rear edge and also hinged intermediately and parallel to the rear edge so that the front portion may be folded to assume a nearly vertical

position and to then act as a card holder, the two said hinge members being adapted to open out sufficiently to permit the said cylinder to be removed from the said casing, a flange on one end of said cylinder, notches on the periphery of said flange, a downwardly projecting pin on the underside of said wrist support and adapted to engage one of said notches by pressure of said wrist.

In testimony whereof we affix our signatures.

GEORGE A. MORRIS.
C. SPENCER PALLOT.
